UNITED STATES PATENT OFFICE.

SIDNEY GEORGE BROWN, OF BOURNEMOUTH, ENGLAND.

RELAY.

SPECIFICATION forming part of Letters Patent No. 666,954, dated January 29, 1901.

Application filed March 15, 1899. Serial No. 709,150. (No model.)

To all whom it may concern:

Be it known that I, SIDNEY GEORGE BROWN, electrician, a citizen of the United States, residing at Van Buren, Poole road, Bournemouth, in the county of Hants, England, have invented certain new and useful Improvements in Relays for Use on Telegraph, Cable, and other Lines, of which the following is a specification.

10 This invention relates to improvements in relays for use on submarine cable and other telegraph lines.

The unsuitability of ordinary relays arises from the character of the arrival-current from 15 long cable-circuits, especially if worked at fast siphon-recorder speed, where the signals are read more from their general outline than from any definite movement of the siphon-arm. It is therefore important that the relay 20 should magnify the arrival-currents in a continuous manner.

Now this invention has for its object the continuous amplification of the arrival signaling-currents, whereby less-sensitive recording instruments may be used and repetition 25 or translation from one line-section to another may be effected without appreciably reducing the speed of signaling.

According to this invention I employ the 30 feeble arrival-current from the main line to operate means for inducing a stronger relay-current.

In order that the invention may be clearly understood and readily carried into effect, I 35 will now proceed to describe the same fully with reference to the accompanying drawings, in which—

Figure 1 is a diagrammatic view of one arrangement of apparatus according to my invention, in which I employ two suspended coils. Fig. 2 is a diagram showing a slight modification of the arrangement shown in Fig. 1. Fig. 3 is a diagram showing an arrangement in which no rectifier is employed 45 in the relay-circuit. Fig. 4 shows an arrangement of apparatus connected in parallel in which one suspended coil only is used. Fig. 5 shows an arrangement of apparatus connected in series in which one suspended coil 50 only is used. Fig. 6 shows an arrangement of apparatus in which two stretched wires replace the suspended coils.

Referring to Fig. 1, A is a light-wire coil delicately suspended in the field of an alternating-current magnet *a*, and B is another 55 light-wire coil delicately suspended in the field of a powerful direct-current electro or permanent magnet *b* and connected to the coil A by a suitable strip of insulating material C. The coils A and B are normally 60 suspended so that their planes are parallel to the north and south lines of their respective magnets and that they are capable of turning on their central longitudinal axes.

D is an electric battery, the direct current 65 from which is conducted by wires *d d* through a rotating commutator or transformer E, whence it is conducted as an alternating current by wires *a' a'* to excite the magnet *a*. I preferably insert a condenser K in the alternating-current circuit *a'* to neutralize self-induction in the coils of the magnet *a*.

F F are wires for conducting the induced current from the coil A to a rotating commutator or rectifier *e*, whence it passes as a direct current to the relay-circuit G G. The commutators E and *e* are mounted, preferably, on the same spindle, so as to work in step.

H H are the main-line conductors, connected to the coil B.

Referring to Fig. 2, the coils A and B, instead of being suspended one beneath the other, are placed side by side and connected by two silk cords *c c* or their equivalent, the 85 arrangement of the apparatus in this case being otherwise the same as that shown in Fig. 1. I prefer to place the ends of the cords *c c* attached to the coil B farther apart than the opposite ends of the said cords, attached to the 90 coil A, in order to obtain as great a movement as possible in the coil A.

Under normal conditions the coils A and B remain stationary; but upon the arrival-current from the main line circulating in the 95 coil B this coil is turned out of its plane and being connected to the coil A turns the latter coil also out of its plane, so that the magnetic lines of force from the alternating-current magnet *a* cut it and induce a voltage proportional to the sine of the angle of deflection. This induced alternating current passes through the conductors F to the rectifier *e*, from whence it passes as a direct current to 100

the relay current-circuit G G. If therefore a siphon recorder or relay or other suitable instrument or instruments are inserted in this relay-circuit, the induced voltage will cause a current to flow which will work such instrument or instruments.

K² is a condenser which may or may not be shunted, with a resistance R for neutralizing the self-induction, if any, in the relay-circuit.

- 10 If the relay-circuit possessed capacity in place of self-induction, then K² would be replaced by a coil possessing self-induction. K² and R may be placed not where shown, but the other side of the rectifier e, in series with the leads F F. By thus altering the value of the capacity or self-induction in the outside suspended-coil relay-circuit the suspended coil can be made to alter its period of vibration. For instance, by adding capacity to the suspended-coil circuit the suspended coil has a tendency to twist itself out of the magnetic field, while if self-induction is added to the suspended-coil circuit the suspended coil has a tendency to move in the opposite direction
- 25 or back into the magnetic field. It is therefore essential that the outside suspended-coil relay-circuit should possess the proper amount of capacity or self-induction for correct working. In the same way the alternating-current coil A could be made to work more efficiently and effectively when any of the leads F F or G G are short-circuited by condensers, resistances, or induction-shunts; but what their value should be or where placed entirely
- 30 depends upon the character of the receiving instrument placed across the leads G G.

Referring to Fig. 3, a similar construction to the foregoing figures is here shown, B being the coil suspended in the field of the direct-current magnet b; A, the coil suspended in the field of the alternating-current magnet a; c c, the cords connecting the coils A and B, and H H the main-line conductors connected to the coil B. In this arrangement, however, the rectifier is dispensed with, the induced-alternating-current conductors F F being directly connected to a third coil A*, suspended in the field of an alternating-current magnet a*. The alternating-current magnets are excited by a transformer or its equivalent, one of the circuits having a condenser K* in circuit. The arrival-current operates the coils A and B, as previously described, and the induced current passing through the coil A* causes movements therein which may be employed to operate a pointer and stops or other instrument or instruments. The condenser K* alters the relative position with respect to time of the rise and fall of the magnetic fields of the magnets a and a*, and thus prevents, as far as possible, any back action of the induced current in the suspended coil of the magnet a* on that of the suspended coil in the magnetic field of the magnet a.

65 Referring to Fig. 4, a single coil A is suspended in a plane parallel to the north and south poles of an electromagnet a, excited by

a fluctuating direct current produced by a battery D, having in circuit a transformer l, or other suitable means may be employed for producing this fluctuating direct current. H H are the main-line conductors, and F F are the induced-alternating-current conductors. e is a rotating rectifier mounted in the same spindle with a synchronous motor E. G G 75 are the relay-circuit conductors, and L is an induction-coil. When the arrival main-line current passes through the coil A, the latter is turned out of its plane, and consequently cut by the fluctuating magnetic lines of force 80 of the magnet a and an alternating current thereby induced which passes by the conductors F F, through the rectifier e, and thence as a direct current to the relay-circuit G G. The coil L resists the alternating induced 85 current and prevents its passing back to the main line, while at the same time allowing the direct main-line current to pass. It will be understood that the transformer l may be replaced by any other means for producing 90 an alternating current—say by means similar to those shown in Fig. 1—or an alternator may replace l directly, when the rectifier e could for convenience be coupled directly to the shaft. The battery D may also be replaced by other means for producing a direct current, such as a dynamo. It will be also understood that the suspended coil A may not only consist of a one-coil circuit, but might also consist of two or more circuits fastened together in parallel. If there were two divisions in the coil A, the current from the lines H H might pass around one of these, while the other might be exclusively reserved for the relay-current F F G G.

105 Referring to Fig. 5, a single coil A is suspended in a plane parallel to the north and south poles of a fluctuating-direct-current magnet excited as described with reference to Fig. 4. H H are the main-line conductors. F F conduct the induced current through the commutator e, and G G is the relay-circuit. E is the synchronous motor. L' and L² are induction-coils. L³ is an inductive or magnetic shunt. K' and K² are condensers. The 110 arrival-current passing through the coil A turns it out of its plane, and an alternating current is induced, as previously described. This induced alternating current passes by the current F F through the rectifier e and thence as a direct current to the relay-circuit 115 G G. The inductive shunt L³ prevents the induced alternating current returning directly to earth, but allows the direct main-line current to pass. The arrangement of the condenser K' and the induction-coil L² enables the induced alternating current to return by the main-line conductor if L' is placed in the line and at the same time prevents the direct 120 main-line current being short-circuited. The 125 condenser K², placed across the leads G G, short-circuits the said leads and allows alternating currents to pass, while opposing the 130 passage of direct currents. Any direct cur-

rent that may pass through the rectifier *e* from the leads *F* becomes an alternating current in the leads *G*, and such alternating current is short-circuited by the condenser *K*² before it can reach instruments placed in the relay-circuit. A direct current on one side of the rectifier *e* becomes an alternating current on the other side of the said rectifier, and it is obvious that it is not necessary to employ both the condenser *K*² and the inductive shunt *L*³, although in practice I prefer to do so. Moreover, as in Fig. 1, capacity and self-induction would be placed in any convenient part of the circuit to neutralize any inductive or capacity effects on the suspended coil *A*. The induction-coil *L'* may be placed in the main circuit for the same purpose as in Fig. 4.

Referring to Fig. 6, *A* and *B* are wires respectively stretched between suitable terminal screws. *b* may be a permanent magnet, between the poles of which the wire *B* passes. *H H* are the main-line conductors, and *K*³ is the usual receiving-condenser in the main-line circuit. *K*⁴ is a condenser to neutralize self-induction in the coils of the magnet *a*. *a* is an alternating-current electromagnet, between the poles of which the wire *A* passes. *i* is a strip of paper or its equivalent connecting the stretched wires *A* and *B*. *l'* is a transformer or its equivalent, for exciting the electromagnet *a*. *l*² is a compensating transformer which might have been wound on the alternating electromagnet *a* and is for the purpose of preventing the stretched wire *A* from inducing any voltage when at rest. *E* is a synchronous motor, and *e* is a rectifier mounted on the same spindle. *F F* are the induced-alternating-current conductors, and *G G* is the direct-relay-current circuit. When the arrival-current passes through the stretched wire *B*, situated in the field of the magnet *b*, it causes the said wire to move out of its normal position, and as the wire *B* is connected to the wire *A* by the strip *i* the wire *A* will also move out of its normal position in the field of the alternating-current magnet *a* and an alternating current will be induced which passes through the commutator *e* to the relay-circuit. The stretched wires *A* and *B* will be seen to merely replace the suspended coils, (shown in Figs. 1 and 2,) and it is obvious that a single stretched wire may be used in a similar manner to the single-coil, (shown in Figs. 4 and 5,) a compensating transformer being generally required to prevent the said stretched wire from inducing any voltage when at rest.

In Figs. 4, 5, and 6 also the rectifier *e* may be dispensed with and replaced by a coil suspended in the field of an alternating-current magnet in a similar manner to coil *A*^{*}, Fig. 3.

What I claim is—

1. In telegraphic relay apparatus, an alternating-current electromagnet, means included in the relay-circuit and suspended in the field of said magnet and adapted to be moved by the signaling-currents received

from a line or cable so as to induce alternating relay-currents, and means for enabling the said relay-currents to operate instruments in the relay-circuit, substantially as described. 70

2. In telegraphic relay apparatus an alternating-current electromagnet, means included in the relay-circuit and suspended in the field of said magnet and adapted to be moved by signaling-currents received from a line or cable so as to induce alternating relay-currents, and means for converting said alternating relay-currents into direct currents for operating instruments in the relay-circuit, substantially as described. 75 80

3. In telegraphic relay apparatus, an alternating-current electromagnet, a condenser for neutralizing self-induction in the coils of said electromagnet, and a coil included in the relay-circuit and suspended in the field of the alternating-current electromagnet and adapted to be moved by signaling-currents received from a line or cable so as to induce alternating relay-currents, substantially as described. 85 90

4. In telegraphic relay apparatus, an alternating-current electromagnet, a condenser for neutralizing self-induction in the coils of said electromagnet, a coil included in the relay-circuit and suspended in the field of the alternating-current electromagnet and adapted to be moved by the signaling-currents from a line or cable, and means for converting the alternating currents induced in the coil, when thus removed, into direct currents for operating instruments in the relay-circuit, substantially as described. 95 100

5. In telegraphic relay apparatus a coil suspended in the field of a direct-current magnet and adapted to be moved by the arrival signaling-currents from a line, another coil suspended in the field of an alternating-current magnet and attached to the first-mentioned coil so as to move therewith and to induce an alternating relay-current, and a rectifier through which the said alternating induced current passes before being led to instruments in the relay-circuit, substantially as described for the purpose specified. 105 110 115

6. In telegraphic relay apparatus, an alternating-current electromagnet means included in the relay-circuit and suspended in the field of said magnet and adapted to be moved by signaling-currents received from a line or cable so as to induce alternating relay-currents, means for enabling the said relay-currents to operate instruments in the relay-circuit, and means for neutralizing self-induction and capacity in the relay-circuit, substantially as described, for the purpose specified. 120 125

7. In telegraphic relay apparatus, an alternating-current electromagnet, means included in the relay-circuit and suspended in the field of said magnet and adapted to be moved by signaling-currents received from a line or cable so as to induce alternating relay-currents, a rectifier through which the said relay-currents pass before being led to instru- 130 135

ments in the relay-circuit, and means for neutralizing self-induction and capacity in the relay-circuit, substantially as described for the purpose specified.

- 5 8. In telegraphic relay apparatus, a coil suspended in the field of a direct-current magnet and adapted to be moved by the arrival signaling-currents from a line, another coil suspended in the field of an alternating-current magnet and attached to the first-mentioned coil so as to move therewith and to induce an alternating relay-current, means for exciting the alternating-current magnet, a condenser for neutralizing self-induction in

the coils of the alternating-current magnet, 15 a rectifier for converting the induced alternating current to a direct current, and means for neutralizing self-induction and capacity in the relay-circuit, substantially as described for the purpose specified.

20

In testimony whereof I have hereunto set my hand, in presence of two subscribing witnesses, this 27th day of February, 1899.

SIDNEY GEORGE BROWN.
